UNITED STATES PATENT OFFICE.

ALFRED COPONY, OF CHICAGO, ILLINOIS, ASSIGNOR OF ONE-HALF TO CHARLES R. COOPER, OF CHICAGO, ILLINOIS.

FREIGHT-CAR CONSTRUCTION.

1,247,083.

Specification of Letters Patent. Patented Nov. 20, 1917.

Application filed April 7, 1916. Serial No. 89,699.

To all whom it may concern:

Be it known that I, ALFRED COPONY, subject to the Emperor of Austria, residing at Chicago, in the county of Cook and State of Illinois, have invented new and useful Improvements in Freight-Car Construction, of which the following is a full, clear, concise, and exact description, reference being had to the accompanying drawing, forming 10 a part of this specification.

My invention relates to freight car construction, and more specifically to the construction of grain cars.

One of the objects of my invention is to 15 provide an improved sealing strip for the joint between the siding and flooring of a grain car which will be simple in construction and durable, and will not be caused to leak by the racking or distortion of the car.

20 Further objects of my invention will appear from the detailed description to follow taken in connection with the appended claims.

25 In the drawing, the figure shows a perspective view of part of a grain car embodying my invention.

Referring to the drawing in detail, the parts of the car shown comprise the steel center sills 10, the steel side sill 11, the 30 wooden flooring 12 resting on the sills 10 and 11, the post 13 and the steel Z-bar 14 for supporting the wooden siding 15 and the sealing strip 16 for the joint between the siding and the flooring. This sealing 35 strip 16 may be formed of an integral piece of sheet metal shaped to form a vertical portion 17 secured to the siding 15 in any suitable manner, as by nails 18, a horizontal portion 19 lying between the lower edge of the siding 15 and the flooring 12, a vertical portion 20 extending over the outer edge of the flooring 12 and a horizontal portion 21 lying against the bottom of the flooring 12 and secured thereto in any suitable manner 45 as by nails 22.

It will be seen that the construction of this sealing strip is such that the joint will not be caused to leak even if the lower edge of the siding should draw away from the 50 flooring 12, due to the racking of the car or the warping of the siding, as the portions 20 and 21 will still be effective to prevent any leakage of the grain or other material in the car.

Having thus described my invention what I claim as new and desire to secure by Letters Patent is:—

1. A freight car comprising wooden siding and wooden flooring, the lower edge of said siding being above the outer edge of the flooring, and a sealing strip for the joint between the siding and flooring comprising a portion lying against the inside of the siding, a portion lying between the lower edge of the siding and the flooring, a portion extending over the outer edge of the flooring, and a portion lying against the bottom of the flooring.

2. A freight car comprising wooden siding and wooden flooring, the lower edge of said siding being above the outer edge of the flooring, and a sealing strip for the joint between the siding and flooring comprising a portion secured to the inside of the siding, a portion lying between the lower edge of the siding and the flooring, a portion extending over the outer edge of the flooring, and a portion secured to the bottom of the flooring.

3. A freight car comprising wooden siding and wooden flooring, the lower edge of said siding being above the outer edge of the flooring, and a sealing strip for the joint between the siding and flooring comprising a portion lying against the inside of the siding, a portion lying between the lower edge of the siding and the flooring, and a portion extending over the outer edge of the flooring.

4. A freight car comprising wooden siding and wooden flooring, the lower edge of said siding being above the outer edge of the flooring, and a sealing strip for the joint between the siding and flooring comprising a portion lying against the inside of the siding, a portion lying between the lower edge of the siding and the flooring, a portion extending over the outer edge of the flooring, and means for securing said sealing strip to said siding and to said flooring.

5. A freight car comprising wooden siding and wooden flooring, the lower edge of said siding being above the outer edge of the flooring, and a sealing strip for the joint between the siding and the flooring comprising a portion lying between the lower edge of the siding and the flooring, a portion extending upwardly from said first

portion and secured to said siding, and a portion extending over the outer edge of the flooring.

6. A freight car comprising wooden siding and wooden flooring, the lower edge of said siding being above the outer edge of the flooring, and a sealing strip for the joint between the siding and the flooring comprising a portion lying against the bottom

of the flooring, a portion extending over the outer edge of the flooring, a portion lying between the lower edge of the siding and the flooring, and a portion extending upwardly from said last portion and secured to said siding.

In witness whereof, I have hereunto subscribed name.

ALFRED COPONY.
